DISPLAY FIXTURE FOR HANDKERCHIEFS

Nelly Gerstle, Larchmont, N. Y., assignor to Altshul, Stern & Co., Inc., New York, N. Y., a corporation of New York

Application May 1, 1952, Serial No. 19,554

Term of patent 14 years

(Cl. D80—1)

To all whom it may concern:

Be it known that I, Nelly Gerstle, a citizen of the United States and a resident of Larchmont, county of Westchester, and State of New York, have invented a new, original, and ornamental Design for a Display Fixture for Handkerchiefs, of which the following is a specification, reference being had to the accompanying drawings, forming part thereof.

Figure 1 is a perspective view, from the front, of a display fixture for handkerchiefs, showing my new design; the two handkerchiefs being indicated in dotted lines for illustrative purposes;

I claim:

The ornamental design for a display fixture for handkerchiefs, substantially as shown and described.

NELLY GERSTLE.
